DISPENSING BOTTLE CAP

George J. McCabe, Fargo, N. Dak.

Application February 24, 1936, Serial No. 65,458

1 Claim. (Cl. 221—148)

The invention relates to a dispensing cap for bottles and more especially to a bottle closure and dropper.

The primary object of the invention is the provision of a cap of this character, wherein the same when worn upon the mouth of a bottle will enable the liquid content to be dispensed therefrom in drops and when the bottle is in upright position the same will be closed to eliminate leakage of the content of the bottle, the cap being of novel construction and the dropping of the liquid is effected by a depressible bulb fitted with said cap.

Another object of the invention is the provision of a cap of this character, which is extremely simple in construction, thoroughly reliable and efficient in its operation, neat in appearance, readily and easily applied to and removed from a bottle neck, possessing but few parts, and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claim hereunto appended.

In the accompanying drawing:

Figure 1 is a fragmentary elevation of a bottle showing the cap constructed in accordance with the invention applied thereto.

Figure 2 is a sectional view on the line 2—2 of Figure 1 looking in the direction of the arrows.

Figure 3 is an elevation partly in section showing the dispensing nipple adjusted for permitting liquid to be dropped from the bottle.

Figure 4 is a bottom plan view of the cap removed from the bottle.

Similar reference characters indicate corresponding parts throughout the several views in the drawing.

Referring to the drawing in detail, A designates generally a portion of a bottle having an externally threaded mouth end 10 for the fitting thereon of the dispensing cap constituting the present invention and hereinafter fully described.

This dispensing cap comprises a collar-like body 11 formed with an internally threaded inner end 12 for detachable engagement with the mouth end 10 of the bottle A while the thickened outer end 13 is formed with a central dispensing opening 14, the wall of such opening being outwardly flared and covering this outer end 13 is a rubber compressible bulb 15, it having marginally thereof an internal bead 16 fitting in an annular seat 17 formed externally in the

thickened outer end 13 for the coupling of such bulb with the body 11 as will be clearly apparent from Figures 2 and 3 of the drawing.

The bulb is formed with a central inwardly directed stem 18 terminating in a conical shaped valve 19 which is normally seated against the inner end of the opening 14 as provided in the thickened outer end 13 so that this opening 14 will be closed and on depressing the bulb 15 the opening 14 will be cleared to permit the discharge of the contents of the bottle A therethrough.

Adjustably threaded laterally in the thickened outer end 13 of the body 11 is a dispensing nipple 20, the socket for the said nipple being in communication with the opening 14 by a passage 21 and this passage is normally closed by screwing the nipple 20 inwardly in its socket to shut off the passage 21 therefrom. On unscrewing the nipple 20 from its socket the passage 21 is opened so that the contents from the bottle A can be dispensed by flow through the opening 14, passage 21 and nipple 20. The nipple 20 in its construction is in the form of a dropper spout for discharging the contents of the bottle A drop by drop through said nipple when the bottle is inverted and the bulb 15 is depressed.

Normally when the bottle is in an upright position the nipple 20 is screwed completely within its socket to close the passage 21 so that leakage from the bottle is prevented even if the same is inverted.

When it is desired to dispense the contents, the nipple 20 is unscrewed from its socket and on depressing the bulb 15 the valve 19 is unseated and such liquid within the bottle is forced therefrom by air through pressing the bulb 15 for the discharge of liquid through the nipple 20 and the flow of the liquid therethrough can be regulated by adjustment of said nipple.

What is claimed is:

A closure of the character described comprising a collar-like body opening through opposite ends and having an internally threaded inner end for detachable engagement with a bottle neck mouth and having an annular external groove at the other end thereof, a shoulder formed internally of said body to provide a valve seat, an inherently resilient cap-like member covering the outer end of said body and seated in said groove for effecting a depressible bulb, a valve depending centrally from said bulb and normally engaging the valve seat, and a pouring nipple carried by said body and having communication with the bottle mouth at the interior of said body.
